UNITED STATES PATENT OFFICE

2,424,356

CLOSURE FOR NONREFILLABLE CONTAINERS

Alberto Reguero González, Habana, Cuba, assignor of eighty per cent to Florencio Sierra More, Habana, Cuba

Application November 1, 1945, Serial No. 625,998
In Cuba October 9, 1945

2 Claims. (Cl. 215—25)

1

This invention relates to closures for nonrefillable containers, and its object is to provide an improved closure for bottle or other containers, that will allow the free passage of the contents therefrom, but prevents unauthorized refilling after the original contents has been dispensed.

In describing the invention in detail, reference will be had to the accompanying drawing forming part of my application, and in which:

Fig. 1 is a longitudinal sectional view of the closure of this invention, attached to the neck of a bottle, with the parts in normal position.

Fig. 2 is a similar view showing the bottle inverted for pouring the contents therefrom and through the closure.

Fig. 3 is an outer view of the closure body.

Fig. 4 is a top plan view of same.

Fig. 5 is a view of the closure inner element wherein a stem-valve is adapted to actuate.

Fig. 6 is a top plan view of said element.

Fig. 7 is a view of the stem-valve adapted to actuate within the closure.

Fig. 8 is a top plan view of the stem-valve and its lower disc.

Fig. 9 is a view of the closure lower portion which partially remains within the bottle neck.

Fig. 10 is a top plan view of said portion.

Referring to the drawing, 1 indicates the neck of a bottle on the upper end 2 of which the closure normally rests. The closure, which may be made of glass or the like, will preferably be made of a plastic material, and it includes a hollow cylindrical body 3 in the shape of an inverted cup having its upper end provided with a central opening 5 and its lower end provided with an outer annular flange 4. Said body 3 has arranged at its inner upper portion and formed integrally therewith a disc 7 having two opposed vertical holes 8—8. At a short distance below said disc 7, said body 3 is provided with inner threads 6 adapted to threadedly receive the upper end of a partially hollow cylindrical body 10 having an upper solid middle portion provided with outer threads 10' and a lower hollow portion 12 which is provided at its lower end with an outer annular flange 11 having two opposed peripheral notches 13—13, said flange 11 having the same diameter as the annular flange 4 of the body 3.

The partially hollow cylindrical body 10 has at the centre of its solid portion a vertical square perforation 15 and at the lower face of said solid portion there are provided two opposed angular conduits 16—16 and in communication with said central square perforation 15, said solid portion

2

being also provided at its lower face with two opposed vertical pins 14—14 in alignment with said conduits 16—16.

Within said square perforation 15 there is 5 adapted to freely slide a solid square stem 17 having an upper horizontal perforation 21 and a lower horizontal perforation 20, both perforations being in communication by a central vertical conduit 22, and said stem having its lower 10 end fixedly secured to the central portion of a disc 18 which is provided with two vertical opposed holes 19—19.

Within the lower hollow portion 12 of the partially hollow cylindrical body 10 (Fig. 5) is inserted a solid cylindrical body 23 (Fig. 9) the lower middle portion of which normally remains within the bottle neck, and said solid cylindrical body 23 has at its peripheral surface near its upper end an annular flange 24 provided at its 20 upper edge with two opposed pins 25—25, said annular flange 24 serving as a seat for the closure on the upper end of the bottle, and said pins 25—25 being adapted to be inserted in the notches 13—13 of partially hollow cylindrical body 10 (Fig. 5).

Said solid cylindrical body 23 (Fig. 9) has at 25 its top plane face two opposed pins 26—26 which are equidistant with two vertical conduits 27—27, said pins 26—26 being adapted to be received in 30 the opposed vertical holes 19—19 of the disc 18 of stem 17.

As it will be obvious, the run of the stem 17 is limited by the pins 14—14 inferiorly carried by the partially hollow cylindrical body 10 (Fig. 35 5) and the top plane face of the solid cylindrical body 23 (Fig. 9).

The closure is secured exteriorly to the bottle neck by means of wax, gelatine or a plastic material, or by any other suitable means that 40 cannot be removed from the bottle neck without breakage or damage to the bottle or closure.

An attempt to inject liquid into the closure in the normal position of the latter as shown in Fig. 1 will be useless, by reason of the fact that 45 the upper horizontal perforation 21 of the stem 17 is not in communication with the space provided between the disc 7 of hollow body 3 and the top portion of the partially hollow cylindrical body 10, and the liquid injected will not find 50 a way down into the closure beyond said space.

Liquid cannot be injected into the bottle in the position of the latter as illustrated in Fig. 2, for the pressure exerted by the liquid entering the closure will strike against the top face of disc 55 18 of stem 17 and force the former down to its

normal position of obturation of conduits 27-27 of solid cylindrical body 23.

The operation of this closure is as follows: When it is desired to pour the contents of the bottle therefrom, the bottle is tilted, whereupon the stem 17 will slide onward within the central square perforation 15 until the top face of the disc 18 inferiorly carried by it will rest on the pins 14-14 disposed on the lower face of partially hollow cylindrical body 10, and the upper horizontal perforation 21 of the stem 17 will be in communication with the space between the disc 7 of body 3 and the top face of partially hollow cylindrical body 10 and the lower perforation 20 of the stem 17 will register with angular conduits 16-16 of partially hollow cylindrical body 10. Outer air entering in the opening 5 of the top portion of hollow body 3 will pass through hole 8 of disc 7, upper perforation 21, central conduit 22 and lower perforation 20 of stem 17, angular conduit 16, hole 19 of disc 18 of stem 17, and vertical hole 27 of the solid cylindrical body 23. Obviously, liquid from the bottle will be permitted to flow freely through opposed perforations and conduits of the closure parts, to find its way out through upper opening 5 of hollow body 3.

Many changes may be made in the shape and in the nature of the material of which the closure is formed, provided that such changes fall within the scope of the appended claims.

What I claim is:

1. A closure for non-refillable containers, comprising a hollow cylindrical body of inverted cup shape provided with a top central opening and having arranged therein and formed therewith a perforated disc, said cylindrical hollow body carrying at its lower end an outer annular flange, a partially hollow cylindrical body arranged within said hollow body and provided at its upper solid middle portion with a vertical central square perforation and at the lower face of its upper solid portion with two opposed pins and two opposed angular conduits and in communication with said central square perforation, said partially hollow cylindrical body being also provided at the end of its lower hollow portion with an outer annular flange on which normally rests the outer flange of said hollow cylindrical body, a solid cylindrical body inserted in the lower hollow portion of said partially hollow body and having two opposed vertical perforations and two opposed pins at its top face, said solid cylindrical body being provided at its peripheral middle portion with an outer annular flange having two pins at its upper edge, a solid square stem partly inserted loosely in the central perforation of said partially hollow cylindrical body and being provided with transverse perforations one of them adapted to register with the angular conduits of said partially hollow body, in the inverted position of the container, in which the other transverse perforation of said stem is above the partially hollow cylindrical body said square stem

having its lower end fixedly secured to the middle portion of a disc provided with opposed vertical holes, and means for securing the closure exteriorly on the container neck.

- 5 2. A closure for non-refillable containers, comprising a hollow cylindrical body of inverted cup shape provided with a top central hole and having its lower end provided with an outer annular flange, said hollow cylindrical body having arranged therein and formed therewith a disc provided with two vertical opposed holes and having inner threads arranged at a short distance beneath said disc, a partially hollow cylindrical body having an upper solid portion provided with a vertical central square perforation and provided at its lower face with two angular conduits and in communication with said central square hole, said partially hollow cylindrical body being provided at its lower hollow end with an outer annular flange having two opposed peripheral notches and being normally in contact with the outer annular flange of said hollow cylindrical body, and the solid portion of said partially hollow cylindrical body being provided with outer threads to be threaded on the inner threads of said hollow cylindrical body, a solid cylindrical body the lower portion of which normally remains lodged within the container neck, said solid cylindrical body carrying at its middle peripheral portion an outer annular flange adapted to serve as a seat for the closure on the container neck and having at its upper edge two opposed pins adapted to be inserted in the peripheral notches of the partially hollow cylindrical body, and said solid portion having at its top plane face two opposed pins and two equidistant vertical holes serving as air inlet and liquid outlet, a solid square stem partially inserted and freely slidable within the central square hole of said partially hollow cylindrical body and having two transverse perforations, one of said transverse perforations being adapted to register with said angular conduits in the inverted position of the container while the other transverse perforation is above the partially hollow cylindrical body in communication by a central vertical conduit, said solid square stem having its lower end fixedly secured to the middle plane portion of a disc provided with two opposed vertical holes, and means for securing the closure exteriorly to container neck and consisting of a melted layer of plastic material.
